(57) **CLAIM**

The ornamental design for a suction nozzle for vacuum cleaner as shown and described.

DESCRIPTION

1. Suction nozzle for vacuum cleaner

1.1: Perspective

1.2: Left

1.3: Right

1.4: Top

1.5: Bottom

1.6: Front

1.7: Back

The broken lines depict portions of the suction nozzle for vacuum cleaner that form no part of the claimed design; the parallel thin lines and the radial thin lines in the reproductions represent contours only and do not illustrate an ornamentation or decoration on the surface of the product.
